Primary Examiner — T. Chase Nelson*(74) Attorney, Agent, or Firm* — Wesley W. Muller(57) **CLAIM**

The ornamental design for a cleat bottom, as shown and described.

DESCRIPTION

FIG. 1 is a perspective view of a cleat bottom according to the present invention;

FIG. 2 is a bottom view of the cleat bottom of FIG. 1;

FIG. 3 is a top view of the cleat bottom of FIG. 1;

FIG. 4 is a right side view of the cleat bottom of FIG. 1;

FIG. 5 is a left side view of the cleat bottom of FIG. 1;

FIG. 6 is a front view of the cleat bottom of FIG. 1; and,

FIG. 7 is a rear view of the cleat bottom of FIG. 1.

The broken lines in the figures merely illustrate the environment for the cleat bottom of the present design and therefore form no part of the claimed design.
